DESIGN FOR A TOLL COIN OR TOKEN DEVICE FOR AUTOMOBILES

Abraham Zitenfield and Joe Weil, New York, N. Y.

Application June 10, 1947, Serial No. 139,566

Term of patent 7 years

(Cl. D52—4)

To all whom it may concern:

Be it known that we, Abraham Zitenfield and Joe Weil, citizens of the United States, residing at New York, in the county of New York and State of New York, have invented a new, original, and ornamental Design for Toll Coin or Token Device for Automobiles, of which the following is a specification, reference being had to the accompanying drawing, forming part thereof.

In the drawing—

Fig. 1 is a top plan view of a toll coin or token device for automobiles, showing our new design;

Fig. 2 is a front elevational view thereof; and

Fig. 3 is an elevational view similar to Fig. 2, but showing the parts separated.

We claim:

The ornamental design for a toll coin or token device for automobiles, substantially as shown.

ABRAHAM ZITENFIELD.
JOE WEIL.
